(57) **CLAIM**

The ornamental design for a task management device, as shown and described.

DESCRIPTION

FIG. 1 is a front, left side perspective view of a task management device showing our new design, according to a first embodiment;

FIG. 2 is a front elevational view of the task management device illustrated in FIG. 1;

FIG. 3 is a rear elevational view of the task management device illustrated in FIG. 1;

FIG. 4 is a left side elevational view of the task management device illustrated in FIG. 1;

FIG. 5 is a right side elevational view of the task management device illustrated in FIG. 1;

FIG. 6 is a top plan view of the task management device illustrated in FIG. 1;

FIG. 7 is a bottom plan view of the task management device illustrated in FIG. 1;

FIG. 8 is a front, left side perspective view of the task management device illustrated in FIG. 1 showing an alternate open position of a left side cover and a rear stand;

FIG. 9 is a rear, right side perspective view of the task management device illustrated in FIG. 8;

FIG. 10 is a rear, left side perspective view of the task management device illustrated in FIG. 8;

FIG. 11 is a front, left side perspective view of a task management device showing our new design, according to a second embodiment;

(Continued)

FIG. 12 is a front elevational view of the task management device illustrated in FIG. 11;
 FIG. 13 is a rear elevational view of the task management device illustrated in FIG. 11;
 FIG. 14 is a left side elevational view of the task management device illustrated in FIG. 11;
 FIG. 15 is a right side elevational view of the task management device illustrated in FIG. 11;
 FIG. 16 is a top plan view of the task management device illustrated in FIG. 11;
 FIG. 17 is a bottom plan view of the task management device illustrated in FIG. 11;
 FIG. 18 is a front, left side perspective view of the task management device illustrated in FIG. 11 showing an alternate open position of a left side cover and a rear stand;
 FIG. 19 is a rear, right side perspective view of the task management device illustrated in FIG. 18; and,
 FIG. 20 is a rear, left side perspective view of the task management device illustrated in FIG. 18.
 The broken lines in the drawing figures depict portions of the task management device that form no part of the claimed design.
